UNITED STATES PATENT OFFICE

146,879

DESIGN FOR A ROAD VEHICLE

Theodore W. Sebern, Burbank, Calif.

Application February 26, 1945, Serial No. 118,149

Term of patent 7 years

(Cl. D14—3)

To all whom it may concern:

Be it known that I, Theodore W. Sebern, a citizen of the United States, residing at Burbank, in the county of Los Angeles and State of California, have invented a new, original, and ornamental Design for Road Vehicle, of which the following is a specification, reference being had to the accompanying drawings, forming part thereof.

Fig. 1 is a side elevation of a road vehicle showing my new design;
Fig. 2 is a top plan view; and
Fig. 3 is an end elevation.
Fig. 4 is a perspective view of a vehicle showing my new design.

I claim:

The ornamental design for road vehicle, as shown.

THEODORE W. SEBERN.
